UNITED STATES PATENT OFFICE.

WILLIAM F. MALLOY, OF PITTSBURG, PENNSYLVANIA.

DESIGN FOR A STANDARD FOR LAMPS, &c.

SPECIFICATION forming part of Design No. 24,906, dated November 19, 1895.

Application filed October 17, 1895. Serial No. 566,010. Term of patent 3½ years.

To all whom it may concern:

Be it known that I, WILLIAM F. MALLOY, a resident of Pittsburg, in the county of Allegheny and State of Pennsylvania, have invented a new and novel Design in Standards for Lamps, &c.; and I do hereby declare the following to be a full, clear, and exact description thereof.

My invention relates to a design for standards or columns for lamps, clocks, and like articles.

The design consists in a standard or column for supporting a lamp or like article, composed of the figure of a boy practically nude, with the exception of a scarf draped around his body and falling down around one of his

legs. One leg is advanced in front of the other in the act of walking. The arms clasp a vase or urn, which is held close to the body.

In the illustration, *a* represents the scarf above mentioned; *b*, the vase or urn carried in the arms of the figure.

I claim—

The design for standards, or columns, for lamps and like articles substantially as herein shown and described.

In testimony whereof I, the said WILLIAM F. MALLOY, have hereunto set my hand.

WILLIAM F. MALLOY.
